UNITED STATES PATENT OFFICE.

CLARENCE H. YOUNG, OF BOSTON, MASSACHUSETTS.

BRICK PALLET.

1,414,061.

Specification of Letters Patent. Patented Apr. 25, 1922.

Application filed June 28, 1921. Serial No. 481,139.

To all whom it may concern:

Be it known that I, CLARENCE H. YOUNG, a citizen of the United States, and a resident of Boston, in the county of Suffolk and State of Massachusetts, have invented an Improvement in Brick Pallets, of which the following description, in connection with the accompanying drawings, is a specification, like characters on the drawings representing like parts.

This invention pertains to improvements in pallets, and more particularly, though not exclusively, to improvements in brick pallets. It is among the objects of the invention to provide a brick pallet of simple construction, great strength and durability, while relatively light in weight, and which is very convenient for manipulation.

In the drawings, which show a preferred form of one embodiment of my invention:

Figure 1 is a bottom view of a brick pallet;

Fig. 2 is a section on the line 2—2 of Fig. 1;

Fig. 3 is a section on the line 3—3 of Fig. 2, being partly in elevation; and

Fig. 4 is an enlarged sectional view on the same line as Fig. 2 of the drawings, showing in detail a preferred form of reinforcing construction used at the ends of the pallet illustrated.

Referring to the drawings and to the preferred form of my invention selected for illustrative purposes, I have shown a pallet having a body portion 8 preferably formed of sheet metal and having downturned lateral flanges 9 preferably terminating in reverse flanges 10 to increase the strength of the pallet longitudinally, while minimizing the danger of injury from careless handling and providing a relatively smooth bearing surface on the bottom of the pallet. The side flanges 9 preferably terminate somewhat short of the ends of the pallet so that the ends of the pallet provide overhanging portions which may be conveniently grasped and which may conveniently fit over suitable supports which may resemble somewhat those illustrated in my co-pending application Serial No. 443,986, filed February 10th, 1921. The ends of the pallet are preferably, as illustrated, reinforced by reinforcing means which preferably take the form, as illustrated, of two pieces of sheet metal bent to overlie and underlie the ends of the pallet. As best

illustrated in Fig. 4, the preferred form of reinforcement provides the portion 11 overlying the end of the body 8, the portion 12 underlying the end of said body, and the cross-flange 13 transverse to the general plane of the body 8 and preferably extending across the under side of the pallet substantially in line with the ends of the side flanges 9. The ends of the cross-reinforcing pieces 13 are preferably bent into general parallelism with the side flanges 9 and may be tucked between the side flanges 9 and reverse flanges 10, where they may be secured by rivets 14. Rivets 15 may be used passing through the ends of the body 8, and the over and underlying reinforcements 11, 12 to secure these parts together.

While I have shown and described a preferred form of pallet, it will be understood that considerable changes from the construction illustrated and described may be made without departing from the scope of my invention, which is best defined in the following claims.

Claims.

1. A pallet comprising a sheet metal body having lateral flanges and an end reinforcing piece providing portions overlying and underlying an end of said body portion, and a cross flange extending between said lateral flanges across said body portion at a point removed from the end of said body.

2. A pallet comprising a sheet metal body having lateral flanges and an end reinforcing piece providing portions overlying and underlying an end of said body portion, and a cross flange extending between said lateral flanges across said body portion at a point removed from the end of said body, the ends of said cross flange bent to reinforce said lateral flanges.

3. A pallet comprising a sheet metal body having lateral flanges and an end reinforcing piece providing portions overlying and underlying an end of said body portion, and a cross flange extending between said lateral flanges across said body portion at a point removed from the end of said body, the ends of said cross flange bent to reinforce said lateral flanges and riveted thereto.

4. A pallet comprising a sheet metal body having lateral flanges terminating short of the ends of said body, and an end reinforcing piece providing portions overlying and underlying an end of said body

portion, and a cross flange extending between said lateral flanges across said body portion at a point removed from the end of said body and substantially aligned with 5 ends of said lateral flanges.

5. A pallet comprising a sheet metal body having lateral flanges, said flanges reinforced by reversely bent edge portions, a reinforcing piece secured to an end of 10 said body and providing a sheet metal cross-reinforcement transverse to the general plane of said body and having its ends entered between said lateral flanges and said reversely bent edge portions.

15 6. A pallet comprising a sheet metal

body having lateral flanges, said flanges reinforced by reversely bent edge portions, a reinforcing piece secured to an end of said body and providing a sheet metal cross-reinforcement transverse to the general plane of 20 said body and having its ends entered between said lateral flanges and said reversely bent edge portions, said cross-reinforcement unitary with an end reinforcement providing portions underlying and overlying the 25 end of said body.

In testimony whereof, I have signed my name to this specification.

CLARENCE H. YOUNG.
